UNITED STATES PATENT OFFICE.

JOSEPH KLEPAC, OF NEW YORK, N. Y., AND LOUIS MATIRKO, OF ELIZABETH, NEW JERSEY, ASSIGNORS TO BRAMBACH PIANO CO., OF NEW YORK, N. Y., A CORPORATION OF NEW YORK.

MACHINE FOR TRIMMING GRAND-PIANO CASES.

Application filed February 21, 1923. Serial No. 620,376.

To all whom it may concern:

Be it known that we, JOSEPH KLEPAC and LOUIS MATIRKO, citizens of the United States, residing at New York, in the county of Bronx and State of New York, and the city of Elizabeth, county of Union, and State of New Jersey, respectively, have invented a new and useful Improvement in a Machine for Trimming Grand-Piano Cases, 10 of which the following is a specification.

The object of our invention is to provide a suitable means for accurately trimming the upper and lower edges of a grand piano case, and particularly a so called baby grand case, 15 by means of which such a case may readily and rapidly be brought to the desired dimensions with accuracy and certainty. This and other objects are accomplished by our invention, certain embodiments of which are 20 hereinafter more particularly set forth.

For a more detailed description of our invention, reference is to be had to the accompanying drawings, forming a part hereof, in which—

25 Figure 1 is a perspective view of a baby grand case in our machine.

Figure 2 shows a cutting device for said machine.

Figure 3 shows this cutter operating on 30 this case while in this machine, and

Figure 4 is a perspective view, taken on the line 4—4 of Figure 3, looking in the direction of the arrows.

Throughout the various views of the 35 drawings similar reference characters designate similar parts.

A piano case 1 is trimmed by being clamped in the pivoted frame 2 while the same is in a vertical position, as shown in 40 Figure 1, and then the frame and case are thrown into a horizontal position, as shown in Figure 3 and saw 3 is applied to cut an edge of the case 1.

The case 1 with the sounding board 4 is 45 placed in a vertical position and clamped in the frame 2 where it is held by clamps 5 (see Figure 4) any number of which may be employed, at any desired location, and each clamp has a handle 6, a screw 7, a nut 8 fixed to the frame 2 and a block 9 pivotally connected to the screw which may be forced against the case 1 so as to hold it firm and true while cut by the saw 3. The case

1 at its open end is further reinforced by internal braces 10 while in the frame 2. 55

Once the case is so clamped in the frame, the frame is thrown into a horizontal position by being turned on the pivots 11 and 12 which rise from suitable supports 13 and 14 and a pivoted leg 15 is lowered to hold the 60 frame in place. This leg is on the heavier side so as to give a firm support. This frame may be locked by a pin and hole construction which are described below. When in this position, the frame has an upper 65 guiding surface 16 and a lower guiding surface 17, both of which are true and designed to receive the saw 3.

The saw 3 is at the lower end of a vertical armature shaft 18 of a motor 19 which receives power through a cable 20. The motor 19 is supported by a frame 21 which rises from a base 22 composed of layers 23, 24, 25 and 26 which are held together by dowels so that one or more layers may be removed if 70 desired, so as to shift the level of the saw 3 with regard to the surface on which the base rests. The base 22 is nearly heart shape in plan and is provided with two curved faces 27 which are adapted to engage a face of a 75 piano case while the saw 3 cuts the same and while the bottom layer rests on the guiding surface 16 or 17.

Sometimes it is desirable to cut the case 1 at two levels. If this be desired, the higher 80 level is first cut all round and then the bottom block is removed and a second cut made at the desired part of the case at the lower level and then an ordinary hand saw used to connect the two cuts. When all cuts from 85 one face are made, say the face 17, the saw is removed, the frame is reversed and if necessary the layer restored to the base of the saw which is then placed on the other face, say the face 16 and a second cut made 90 the same as before. While all cuts are being made, sawdust may be ejected by the saw 3 through an opening 28 in the base 22. After the cuts have been made, as above described, the trimmed off portions are removed, and 95 then the frame is changed to a vertical position and the piano case unclamped and removed, and thereafter a second case may be inserted and treated the same as the first.

It is important that the frame be locked 100 in a horizontal or vertical position so as to

hold the same secure when desired, and this may be done in any of several ways, as by providing the frame with perforations 29 which register with corresponding perforations 30 in the supports 13 and 14 for the pivots 11 and 12, and then providing a pin 31 which may be inserted in or removed from said perforations when they register. A string or chain 32 may be provided to prevent the pin 31 from being lost.

While we have shown and described one embodiment of our invention, it is obvious that it is not restricted thereto, but that it is broad enough to cover all structures that come within the scope of the annexed claims.

Having thus described our invention, what we claim is:

1. Means for receiving and fitting a grand piano case and holding the same, and means above and below said receiving means for guiding a cutting tool while trimming the edges of said case.
2. A frame adapted to receive and fit a grand piano case provided with two pivots, mountings for said pivots and guiding surfaces in different planes for guiding a cutting tool while trimming the edges of a piano case held in the frame.
3. A frame for holding and fitting a grand piano case, means for clamping the case in the frame, means for pivoting the

frame, means for guiding a cutting tool in various planes while trimming the edges of the case and means for supporting one side of the frame while an edge is being trimmed. 35

4. In a frame of the class described, means for receiving, fitting, and clamping a grand piano case, guiding faces in different planes on said frame and means for locking the frame so that either of said faces may 40 be uppermost.

5. A frame for holding and fitting a grand piano case, means on opposite sides of said frame for guiding a cutting tool, and a cutting tool having parts resting on 45 either of said guiding means and parts resting against said piano case.

6. In a machine of the class described, means for clamping, fitting, and holding a grand piano case, guiding means secured to 50 opposite sides of said holding means, a cutting tool with a base adapted to rest on either of said guiding means whereby to trim either edge of the case, said base having several layers, one or more of which may 55 be removed or inserted to change the level at which the cutting tool will operate on a case.

In testimony whereof we have hereunto affixed our signatures.

JOSEPH KLEPAC.
LOUIS MATIRKO.
